(57) **CLAIM**

The ornamental design for a 2-in-1 water sprinkling can, as shown and described.

DESCRIPTION

FIG. 1 is a perspective view of a 2-in-1 water sprinkling can showing our design ;
FIG. 2 is a front elevational view of FIG. 1;
FIG. 3 is a rear elevational view of FIG. 1;
FIG. 4 is a left side elevational view of FIG. 1;
FIG. 5 is a right side elevational view of FIG. 1;
FIG. 6 is a top plan view of FIG. 1;
FIG. 7 is a bottom plan view of FIG. 1; and,
FIG. 8 is a first reference view thereof when in use.
The broken line showing is for illustrative purposes only and forms no part of the claimed design.
